UNITED STATES PATENT OFFICE.

EDWARD OVERALL TALIAFERRO, OF PHILADELPHIA, PENNSYLVANIA.

CAR UNLOADER.

Application filed December 13, 1919. Serial No. 344,570.

To all whom it may concern:

Be it known that I, EDWARD O. TALIAFERRO, a citizen of the United States, and a resident of Philadelphia, in the county of 5 Philadelphia and State of Pennsylvania, have invented certain new and useful Improvements in Car Unloaders, of which the following is a specification.

My invention relates to improvements in 10 car unloaders, and it consists in the constructions, combinations and arrangements herein described and claimed.

The foremost object of my invention is to provide an improved unloader for removing 15 such materials as coal, sand, gravel, crushed stone, slag and the like, from railroad cars or other vehicles, and to either discharge the unloaded material at a fixed point, or at various points along the length 20 of the vehicle which is being unloaded.

A further object of the invention is to provide a car unloader, including a gantree, on which the unloading mechanism is operatively mounted, which is capable of being either fixed in relation to a car, which is made to move beneath the gantree, or movable with respect to the car which in 25 that case is fixed.

A further object of the invention is to 30 provide unloading mechanism for cars, which operates slowly down the length of the car, and removing such material in a swath of a width equal to that of the standard car.

A further object of the invention is to 35 provide a car unloader, which includes a material elevator with adjusting means for fixing it at various positions in respect to the car.

Other objects and advantages will appear in the following specification, reference being had to the accompanying drawings, in which:—

Figure 1 is a side elevation, showing the 45 improved unloader in operative relation to a car which is being unloaded,

Figure 2 is a detail side elevation of the unloader,

Figure 3 is a plan view of the unloader,

Figure 4 is a front elevation, the car which is being unloaded being shown in section,

Figure 5 is a detail perspective view of

the elevator mechanism, showing the fixed elevator guides and the elevator frame mov- 55 able therein,

Figure 6 is a detail cross section taken substantially on the line 6—6 of Figure 5,

Figure 7 is a detail perspective view of the fixed elevator drive gear and its mov- 60 able shaft,

Figure 8 is a detail section of the stationary conveyor drive pinion and its slid- 65 able shaft, and

Figure 9 is a detail view of the wind- 65 ing drum clutch mechanism.

In carrying out my invention I provide a gantree G which is either fixed or movable with respect to the car C, which is to be unloaded, the gantree carrying drive mecha- 70 nism M by means of which the conveyor A and elevator E are simultaneously operated. The elevator E works into material to be unloaded, discharging that material on the lateral conveyor A by which in turn 75 the material is dumped into a suitable receptacle, and the elevator being substantially equal in width to the width of the car C, practically removes all of the material as the unloading operation progresses. 80

Either the car or gantree are made to move, one in respect to the other, and in the former case, which is preferable, cables 1, 2 are attached at 3 to the car C and run over drums 4, 5 on the gantree G. These drums 85 are operated either fast or slow and cause the car C to move beneath the gantree, or in other words, the material to be unloaded is continuously moved up against the elevator E which promptly disposes thereof. 90

This gives a general idea of the invention, but in order that the construction may be more clearly understood, the following description is sub-divided into major subjects so that each part of the invention can be minutely considered by itself. This description is followed by a résumé of the operation. Consider first the gantree G. This gantree, which consists of a frame 6 of suitable size and design, is mounted on trucks 100 7, with wheels 8 which run on rails 9 disposed a suitable distance outside of the ordinary railroad track rails 10. By this arrangement, either the gantree may be made to move over the car C, or the car C made 105 to move beneath the gantree, depending on

the manner in which it is desired to have the material discharged.

In the present instance, it is desired to have the car C move in respect to the gantree, and to further this purpose, the wheels 8 are suitably blocked at 11, so that the gantree cannot move. Diagonally opposite ones of the gantree wheels 8, that is to say, those wheels diagonally farthest from each other, are provided with bevel gears 12, (as can be seen in Fig. 3 for example) with which pinions 13 on drive shafts 14, engage. These shafts are suitably supported in bearings 15, and at the opposite ends carry pinions 16 which are driven by bevel gears 17 forming part of the mechanism M. Fixed in any suitable manner to the gantree G, are the guides 18 of the elevator E. These guides are disposed at a slight inclination, and while firmly mounted on the gantree, are also additionally braced by means of the guys 19, which reach from the uppermost caps 20 to various parts of the frame. It is well to now consider the construction of the elevator E. As can be readily seen, the guides 18 consist of parallel members on which the U-shaped channels 21 of the elevator carriage 22 ride. This carriage may be of any suitable shape and design, the only requirement being that it move up and down in respect to the fixed guide so that the buckets 23 on the belt 24 may be brought into proper relationship to the material in the car C for effectively unloading the car.

The weight of the load on the upper side of the belt 24 is supported by supporting rolls 25, which are journalled at 26 on the frame. The belt 24 runs over top and bottom rolls 27, which are journalled in bearings 28 on other parts of the movable frame. This whole structure moves as one, a cable 29 supporting the movable elevator at all times.

This cable runs over a pulley 30 and winds around the elevator drum 31 which is a part of the mechanism M. The other end of the cable 29 is divided at 32, the respective portions running over guide pulleys 33 on the cap 20, then down over the hoisting pulleys 34, suitably carried by the frame 22, back over guide pulleys 35 on each cap 20, being finally secured at 36 to the respective caps in any suitable manner.

By suitably manipulating the hoisting mechanism, that is to say, the hoisting drum 31, the conveyor frame can be raised or lowered in the guides 18 to any desired position, so as to extend as far into the car C as may be desired. In beginning the operation, the elevator frame is slowly lowered so that the buckets 23 can dig their way into the material, close to the bottom of the car. It is not until such position is reached that the mechanism is made to operate so as to pull the car C forwardly.

But when the mechanism is thus operated to pull the car C forwardly, it follows that the material is slowly advanced toward the moving conveyor bucket 23, and since the elevator E is of substantially the same width as the car C a practically complete removal of the material results.

The elevator is driven by a shaft 37 with a bevel gear 38 fixed at the top and a bevel gear 39 relatively stationarily mounted in a bracket 40 on the elevator guide frame. The lowermost gear 39 includes a hub 41, to the bottom of which a plate 42 is secured, for the purpose of holding the gear in place on the bracket 40.

This gear has a spline 43 which occupies the groove 44, extending the full length of the elevator shaft 37, for the purpose of permitting the shaft 37 to slide through the hub of the gear 39 but still maintain the driving connection offered by the spline 43 in the groove 44. The upper gear 38 is in fixed relationship to the gear 45, on one end of the upper roll shaft, a bracket 46 providing the support for the gear 38 as well as the journal for the upper end of the elevator shaft 37.

Meshing with the gear 39 is the bevel pinion 47 on a countershaft 48, on the other end of which there is a sprocket 49 with a chain 50 leading to the sprocket 51 on a second countershaft 52 on the gantree frame platform. This second countershaft 52 has a spur pinion 53 which meshes with a gear 54, the various connections just described being the means whereby the elevator E is operated. It can be easily understood that the elevator itself can be adjusted up and down to suit various conditions, the driving connections always being maintained by virtue of the spline and groove connections 43, 44 already described.

The transverse conveyor A is the next in the order of consideration. The material elevated from the car C by the buckets 23 on the belt 24, is dumped onto the conveyor A, by means of which the material is transported to one side of the gantree G and dumped into a waiting receptacle. This operation follows when the gantree G is stationary and the car C is moved in respect thereto. But in case the car C is made stationary and the gantree G is moved in respect to the car, then naturally it follows that the point of discharge of the transverse conveyor A gradually changes.

There must then be a moving waiting receptacle or there may be a plurality of bins into which the material is dropped. This conveyor consists of a belt 55 moving on end rollers 56, the upper strand of the belt being supported by a plurality of rollers 57. All of the rollers mentioned are suitably journalled in bearings 58 on the conveyor frame 59. A sprocket chain 60, run-

ning over the sprocket 61, on the shaft 62, of the outermost roller 56, drives the conveyor A from the sprocket 63 on a counter-shaft 64, which is journalled in bearings 65.

- 5 A bevel pinion 66 on the extremity of the shaft 64, meshes with a bevel gear 67 on the main counter drive shaft 68 of the mechanism M. This gear is fixed on the shaft 68 so that the conveyor A moves continuously with the elevator E. That is to say, they both move together so as to dispose of the material, but in case it be desired to stop them both, a clutch 69 on the shaft 68 is made use of. This clutch is best described 10 in connection with the actuating mechanism M which is under control of an operator who may stand on the platform 70 on top of the gantree G. It is to be observed that the clutch 69 is to be moved into engagement 15 with a corresponding clutch element 71 of the drive gear 72 on the shaft 68, which is continuously driven by a driver 73 on the main shaft 74 which is operated by the motor 75 through intermeshing gears 76.
- 20 Numerous clutches for various purposes to be explained, are made use of in the mechanism M, but in most instances, the actuating levers or handles are omitted for the purpose of clearness. By reason of the fact 25 that there is a special arrangement for moving the clutches of the pulling drums 4, 5, separate illustration of the handles and connections thereof, is made in detail in Figure 9.

- 30 A movable clutch 77, on the main shaft 74, controls the operation of the shaft 78, on the outermost ends of which are the bevel gears 17 which propel the gantree on the rails 9. This clutch 77 cooperates with the 35 clutch element of the loose gear 79 on the shaft 74, which in turn meshes with the gear 80 on the shaft 78. A suitable reversing mechanism may be embodied in the gear connections, if found necessary, so that the 40 gantree G may be propelled either backward or forward on the rails.

- 45 Consider now the means for moving the car C in respect to the gantree. As already described above, the pulling cables 1, 2 are wound around the pulling drums 4, 5. These drums can be rotated at either high 50 or low speed by clutching in either the sets 81, 82, or 83, 84 of the intermeshing gears between the main counter drive shaft 68 and the shafts 85, 86 of the respective pulling 55 drums. The manner of controlling the clutches is clearly shown in Figure 9.

- 60 Here, the movable clutches 87, 88 are for low speed, while the clutches 89, 90 are for high speed. The respective sets of clutches have pivoted levers 91, 92 which respectively connect with operating levers 93, 94 through links 95, 96. These connections are arranged in such a way that when the respective levers 65 are moved in one direction, as indicated for

example by the arrow, the clutches are moved in, and if the same lever is moved in the opposite direction, the clutches are moved out.

The operation may now be easily followed, 70 and it is thought in view of the above, only a brief résumé will be required in order to complete the understanding of the purpose of the invention. According to the present showing, the gantree G is blocked up on 75 the tracks 9 by means of the blocks 11, so that the gantree is fixedly held from movement. On the contrary, the car C which is to be unloaded, is movable on its rails 10, the car being moved in respect to the elevator E, by means of the pulling cables 1, 2 which at one end are fastened to the car C at 3 and at the other, to the pulling drums 4, 5.

The first thing the operator does is to let 80 the movable elevator carriage 22 down so that the buckets 23 begin to operate on the material in the car C. He does this by gradually clutching in the elevator drum 31, loose on the main shaft 74, and provided 85 with friction clutch mechanism 97. This mechanism also includes the brake drum and band mechanism 98 by means of which the drum 31 is held at various positions, as of course is necessary to support the movable 90 elevator frame 22 in its various adjustments.

During the initial act of lowering the elevator carriage 22 into the material, the elevator and conveyor belts 24, 25 are of course moving to dispose of the material that is 100 being elevated. The bottom of the car C will presently be reached, and when thus reached, the operator grasps the handle 93, for example, throws it over toward the left, as indicated by the arrow in Figure 9, so 105 that the slow clutches 87, 88 are thrown into mesh with the slow sets of gears 83, 84. The car C is now slowly pulled beneath the gantree G, the material in the car being advanced to the moving elevator E, which disposes of the material as already fully set out.

Should it be desired to move the gantree in respect to the car, it becomes necessary to block up the car on its rails, remove the blocks from beneath the wheels 8 of the gantree, but secure the pulling cables 1, 2 in the same places 3 on the car. Now when the drums 4, 5 are started in revolution, the gantree will naturally pull itself over the car performing the same unloading functions as 115 described above.

When it is desired to propel the gantree to other positions, the clutch 77 on the main shaft 74 is thrown in, so that the counter-shaft 78 and the shafts 14 are made to operate, and thereby to propel the gantree.

120 While the construction and arrangement of the improved unloading mechanism as herein described and claimed, is that of a generally preferred form, obviously modified 125 130

cations and changes can be made without departing from the spirit of the invention or the scope of the claims.

I claim:

5. 1. In a car unloader, fixed guides, an elevator on the guides, means for extensibly adjusting the elevator along the guides, and driving means for the elevator, including a member stationary on the guides and a 10 cooperating member carried by the elevator maintaining a permanent driving connection.
15. 2. A car unloader, including a frame with fixed guides and a stationary drive gear, driving means with connections to the gear, and an elevator extensible in respect to the guides, with a permanently operative driving connection, including a shaft 20 slideable in said gear, with spline and groove connections.
25. 3. A car unloader, comprising fixed guides beneath which a loaded car is moved, operating mechanism, an elevator carried by the guides, means actuated by the mechanism enabling extension of the elevator on the guides into the load, operatively associated means for continuously driving the elevator from said mechanism during extension, and means actuated by said mechanism for gradually advancing the car toward the elevator after the bottom of the car is reached.
30. 4. A car unloader, comprising fixed guides beneath which a loaded car is moved, operating mechanism, an elevator carried by the guides, means actuated by the mechanism enabling extension of the elevator on the guides into the load, operatively associated means for continuously driving the 35 elevator from said mechanism during extension, means actuated by said mechanism for gradually advancing the car toward the elevator after the bottom of the car is reached, and means embodied in said advancing means for moving the car at different speeds.
40. 5. A car unloader comprising guides, an elevator on the guides, means to adjust the elevator to various degrees of extension along the guides, operating mechanism for the unloader having a driving connection to the elevator, means for driving the elevator operated by said driving connection, said means including a member stationary 45 on the guides and a cooperating member carried by the elevator and in driving connection with the stationary member, means for receiving and disposing of the discharge

of the elevator, means by which it is actuated from said mechanism, and means also operated from said mechanism for advancing a car over which the unloader is disposed in respect to the elevator.

6. A car unloader comprising a gantree, an elevator carried by the gantree comprising an arrangement of guides suitably fixed thereupon, movable means including channels slideable upon the guides, top and bottom rolls journaled on the movable means, an endless belt with buckets running over said rolls, means carried by the fixed guides and having connections to the movable means to effect various adjustments thereof in respect to the fixed guides, and means carried by the fixed guides arranged to continuously drive the rolls even during adjustments of the movable means.

7. A car unloader comprising a gantree, an elevator carried by the gantree comprising an arrangement of guides suitably fixed thereupon, movable means including channels slideable upon the guides, top and bottom rolls journaled on the movable means, an endless belt with buckets running over said rolls, means carried by the fixed guides and having connections to the movable means to effect various adjustments thereof in respect to the fixed guides, means carried by the fixed guides arranged to continuously drive the rolls even during adjustments of the movable means, and driving mechanism including means to operate said roll-driving means and other means to move a car to be unloaded under the gantree during the operation of the elevator.

8. A car unloader comprising a wheeled gantree, an elevator carried by the gantree comprising an arrangement of guides suitably fixed thereupon, movable means including channels slideable upon the guides, top and bottom rolls journaled on the movable means, an endless belt with buckets running over said rolls, means carried by the fixed guides and having connections to the movable means to effect various adjustments thereof in respect to the fixed guides, means carried by the fixed guides arranged to continuously drive the rolls even during adjustment of the movable means, drivable means in connection with certain wheels of the gantree, and common driving mechanism for furnishing power to both said drivable means and to said roll-driving means.

EDWARD OVERALL TALIAFERRO.
